UNITED STATES PATENT OFFICE.

GEORGE GEYER, OF HAMMOND, INDIANA, ASSIGNOR TO FEDERAL CEMENT TILE COMPANY, OF CHICAGO, ILLINOIS, A CORPORATION OF ILLINOIS.

ROOF STRUCTURE

1,417,513.

Specification of Letters Patent. Patented May 30, 1922.

Application filed March 16, 1921. Serial No. 452,690.

To all whom it may concern:

Be it known that I, GEORGE GEYER, a citizen of the United States, residing at Hammond, in the county of Lake and State of Indiana, have invented a new and useful Improvement in Roof Structures, of which the following is a specification.

My invention relates, more particularly, to roof structures formed of slabs of cement or the like material, ordinarily assembled, to form the roof, in overlapped courses or rows, the slabs of adjacent rows being arranged in staggered relation, my invention relating more especially to the matter of producing water-tight joints between the slabs.

My primary object is to provide joints between the slabs which shall be highly effective in excluding the passage of water through them, and which may be provided at much less cost than hitherto possible; and to accomplish the above especially where the slabs are provided as relatively thin structures.

Heretofore it has been common practice to cover the joints between the opposing edges of slabs arranged in edge to edge relation, by what are known as rolls, which are structures formed separate from the slabs, and of general semi-circular shape in cross-section, these rolls overlying the joints between the slabs. While joints thus provided are highly satisfactory in excluding the passage of water through the joints, the cost of constructing a roof in this manner is quite expensive, and it is one of my objects to provide a joint of such character that such rolls need not be employed.

Referring to the accompanying drawing: Figure 1 is a plan view of a portion of a roof structure constructed in accordance with my invention, the cement at certain of the joints being broken away. Figure 2 is a perspective view of one of the similar slabs. Figure 3 is a broken section taken at the lines 3 on Figs. 1 and 5 and viewed in the direction of the arrows. Figure 4 is a broken section taken at the line 4 on Figs. 1 and 5 and viewed in the direction of the respective arrows; and Figure 5, a broken section taken at the line 5 on Fig. 1 and viewed in the direction of the arrow.

In accordance with the illustrated, preferred, embodiment of my invention, the slab, is provided of the form shown in the

drawings, Fig. 2 showing one of the similar slabs in perspective. The slabs, represented at 6, are provided of rectangular form, and are preferably of the thin type with reinforcement (not shown) disposed in the tensile zone of the slab. The slab is provided along its upper surface adjacent its opposite edges thereof, with upwardly-extending ribs 7 which extend preferably the full length of the slab and afford at opposite edges of the latter, the lengthwise-extending recesses 8. The tile is thickened in a direction lengthwise thereof and along its medial line to form a roll 9 which extends from one end of the slab to a point short of the opposite end thereof, the under side of the slab at the end of the latter to which the roll 9 extends, being recessed as represented at 10.

In the assembling of the slabs to form a roof structure, they are arranged in edge to edge relation as shown in Figs. 1, 3 and 4, to form a plurality of courses, with the upper edges of the slabs of each, except the uppermost, course, overlapped by the lower edges of the courses immediately above them, the slabs of adjacent courses being arranged in staggered relation to cause the joints between the slabs arranged side by side to extend into the recesses 10 of the slabs of the courses next above them, as shown. In the arranging of the slabs in edge to edge relation as stated and shown, the opposing recesses 8 afford at each joint a groove 11 extending lengthwise of the slabs, the adjacent, opposed, edges of the slabs being preferably spaced a slight distance apart as shown in Figs. 1, 3 and 4. In the laying of the slabs any suitable plastic cementitious material, such as that commonly employed to fill the joints between roof slabs, is applied to the upper surfaces of the slabs to extend, preferably, the full length thereof at the joints, the applied material referred to, and represented at 12, being provided of such thickness as to extend into the channel 11, and at least part way down into the spaces between adjacent slabs, and completely imbed the ribs 7, the body of material 12 preferably being so applied that it will present the cross-sectional shape as shown in Fig. 4. Before applying the upper courses of slabs, ribbons 13 of the cementitious material referred to are applied across the upper surfaces of the

slabs adjacent their upper edges to extend at right angles to the length of the slabs and in such position that the lower edges of the slabs next above them will bear down 5 against these ribbons of cementitious material. The masses 12 of cement, especially at the upper ends of the joints over which they extend, are of sufficient volume that when the slabs next above them are applied to position thereon, in staggering relation thereto, the walls of the shallow recesses 10 will cause these masses, where engaged by the row of slabs next above them, to be mashed down, substantially to the cross-sectional shape shown in Fig. 3, thereby causing the cementitious material to completely fill the space presented between the slabs at their recessed portions 10 and the ribbed portions of the slabs immediately beneath 20 them.

It will be noted from the foregoing that the ribs 7 serve to afford, at the juncture of adjacent slabs, the groove 11 which when filled with the cementitious material presents a relatively large cross-section of the material, and at their opposite edges serve to dam the water running down the slabs and to a great degree divert it from the joints between the slabs. 25 By providing the channel 11, the cementitious material 12 is interlocked therewith and held in position relative to the slabs, in a comparatively large body, thereby greatly lengthening the life of the cementitious material. 30

In using the expression "slabs" in the foregoing description and the following claims, I wish to be understood as intending it to express any form of body, such as 40 for example, so called flat slabs or tile, of such character that a roof structure may be constructed therefrom.

While I have illustrated and described a particular construction embodying my invention, I do not wish to be understood as 45

intending to limit it thereto as the same may be variously modified and altered without departing from the spirit of the invention.

What I regard as new, and desire to secure by Letters Patent, is:

1. In combination, slabs arranged side by side in edgewise opposed relation, said slabs presenting a groove at their opposed edges, plastic filling material filling said groove and extending above the upper surface of the slab, and a third slab overlapping said first-referred-to slabs, and containing in its under side at one end a relatively shallow recess at which it overlaps one end of the filled groove and in the assembling of said slabs, directly engage the filling and squeezes the latter into close engagement with the under side of said recess, said filling forming an exposed filler body rendering water-tight the joint between said slabs. 55

2. In combination, slabs arranged side by side in edgewise opposed relation, said slabs presenting an upwardly opening groove at their opposed edges, the upper surface of each of said slabs having an upwardly extending rib extending lengthwise thereof and located between said groove and the main body portion of the slab, and plastic cementitious filling material filling said groove and forming an exposed filler rendering water-tight the joint between said slabs. 70

3. In combination, slabs arranged side by side in edgewise opposed relation, said slabs presenting an upwardly opening groove at their opposed edges, the upper surface of each of said slabs having an upwardly extending rib extending lengthwise thereof and located between said groove and the main body portion of the slab, and plastic cementitious filling material filling said groove and embedding said ribs. 80

GEORGE GEYER.
